O. DOBBELSTEIN

APPARATUS FOR DRYING OR SMOLDERING LOOSE MATERIAL

Filed Nov. 26, 1926

UNITED STATES PATENT OFFICE.

OTTO DOBBELSTEIN, DECEASED, LATE OF ESSEN-ON-THE-RUHR, GERMANY, BY KAROLINE DOBBELSTEIN, ADMINISTRATOR, OF ESSEN-ON-THE-RUHR, GERMANY.

APPARATUS FOR DRYING OR SMOLDERING LOOSE MATERIAL.

Application filed November 26, 1926, Serial No. 150,909, and in Germany November 30, 1925.

This invention relates to improvements in apparatus for drying or smoldering loose material, and more particularly in apparatus comprising a rotary member provided with 5 annular chambers separated from one another by annular heating chambers. The object of the improvements is to provide an apparatus of this class in which the rotary part is separated in an air-tight manner 10 from the chambers receiving the gas or vapor developed from the loose material by heating the same. Another object of the improvements is to provide an apparatus in which loose material which is not subject to sintering can be more readily treated. With these 15 objects in view the invention consists in disposing the said apparatus with its axis of rotation vertically, so that the chambers containing the loose material are horizontal. 20 Thereby water seals can be provided for the rotary drum, and the loose material is supported on the horizontal walls of the chambers.

For the purpose of explaining the invention an example embodying the same has 25 been shown in the accompanying drawing, in which the same reference characters have been used in all the views to indicate corresponding parts. In said drawing,

30 Fig. 1, is a sectional elevation showing the improved apparatus, and

Fig. 2, is a sectional plan view taken on the line 2—2 of Fig. 1.

In the example shown in the drawing the 35 improved apparatus comprises a rotary drum 3 provided at its bottom with an annular rail 4 supported on suitable rollers 5. Further, teeth 8 are secured to the bottom of the drum 3, and the said teeth are in mesh with 40 a bevel gearing 9 for imparting rotary movement to the drum. Below the said drum there is a stationary tubular member 25 which is open at its top and closed at its bottom by a lid 11 provided with a plurality 45 of burners 12 for supplying a heating medium to the drum. At its top the drum is provided with a discharge pipe or stack 6. The drum is provided with superposed pairs of annular plates 7 closed at their outer circumferences and communicating at their inner

circumferences with the inner part of the drum 3 as will be described hereinafter. Between the superposed pairs of plates 7 annular chambers *b* are provided, which are closed at their inner circumferences and open 55 at their outer circumferences, the said chambers being adapted to receive the loose material.

The drum is provided with radial partitions 10 dividing the same into chambers *d* and *e*. The heating chambers *c* provided between the plates 7 are divided by radial partitions *g* extending all through the said chambers into sectional chambers, and each sectional chamber is provided with a radial partition *m* extending from the wall of the drum 3 to a point away from the outer circumference of the plates 7. The wall of the drum 3 is formed with openings *i* and *k* connecting each chamber *d* and *e* with two adjacent sectional chambers *c*. The chambers or passages *d* are open at their bottom ends and closed at their top ends, while the chambers or passages *e* are open at their top ends and closed at their bottom ends. 75

The drum 3 and plates 7 are surrounded by a cylinder 12 divided by a partition 13 into two chambers *s* and *t* each having an outlet 14 and separated from the drum 3 and plates 7, 7 by a foraminated cylinder 15. 80 At one side of the cylinder 12 there is a vertical chamber *p*, and through one side of the said chamber plungers *o* are radially movable: The chamber *p* is adapted to receive the loose material, which material is 85 pushed by the plungers *o* into the annular chambers *b*. Adjacent to the chamber *p* there is an outlet *r* extending the whole height of the drum and adapted to remove the loose material at the end of the smoldering operation. For withdrawing the 90 smoldered material from the chambers *b* into the outlet *r* scrapers *n* are provided, which extend into the chambers *b* to the wall of the drum 3. 95

Water seals *u* and *v* are provided for closing the chambers *s* and *t* and the chambers *b* as against the outer air and the drum 3. As shown in Fig. 1, the uppermost plate 7 is provided with a pair of concentric

- flanges 18 engaged by a downwardly directed flange 19 of the annular jacket *s, t*. In a similar way, an inward extension of the bottom of the jacket *s, t* carries a pair of concentric flanges 20 engaged by a flange 21 depending from the bottom plate 7. The annular spaces included between the flanges 18 and 20 are filled with a suitable sealing liquid.
- 10 In the operation of the apparatus the drum 3 is rotated by means of the bevel gearing 8, 9, heating gas is supplied through the pipes or burners *f*, and the loose material contained within the chamber or hopper *p* is continuously pushed into the chambers *b* by means of the plungers *o*. The heating gas rises within the chambers *d* and flows therefrom through the openings 23 into the heating chambers provided between the plates 7. Within the said chambers the gas flows outwardly and inwardly again, whereupon it is discharged into the chambers *e* and the discharge pipe or stack 6. The direction of the flow of the heating gas has been indicated in the figures by arrows. By the rotary movement of the drum 3 the fuel is gradually carried around to the scrapers *n* by means of which it is delivered through the outlet *r*. The gas developed from the material flows into the chambers *s* and *t* from whence it is removed through the pipes 14. In the retracted positions of the plungers *o* the loose material falls to the front side of the plungers from the side thereof. In such cases in which the said plungers are not located one above the other but are laterally displaced with relation to each other the material drops in front of the said plungers from above.
- 40 By providing horizontal chambers for the loose material now sintering material can be treated.

While in describing the invention reference has been made to a particular example embodying the same, it is to be understood that the invention is not limited to the construction shown in the drawing, and that various changes may be made in the general arrangement of the apparatus and the construction of its parts without departing from the invention.

Claims:

1. An apparatus for heating loose material, comprising a vertical rotary drum provided with annular heating chambers located one above the other and spaced from each other to provide chambers for the loose material, heating means for said heating chambers, means for supplying the loose material to the chambers provided between the heating chambers and to remove the said material therefrom, a stationary jacket surrounding said drum and heating chambers and adapted to collect the gas or vapor de-

veloped from the loose material, and a liquid seal between said jacket and rotary drum.

2. An apparatus for heating loose material, comprising a vertical rotary drum provided with annular heating chambers located one above the other and spaced from each other to provide chambers for the loose material, heating means for said heating chambers, a hopper means for supplying the loose material from said hopper to the chambers provided between the heating chambers simultaneously, means to remove the loose material from said chambers simultaneously to the outlet, and a stationary jacket surrounding said drum and heating chambers and adapted to collect the gas or vapor developed from the loose material.

3. An apparatus for heating loose material, comprising a vertical rotary drum provided with annular heating chambers located one above the other and spaced from each other to provide chambers for the loose material, heating means for said heating chambers, a hopper means for supplying the loose material to the chambers provided between the heating chambers simultaneously, means to remove the loose material from said chambers simultaneously to the outlet, a stationary jacket surrounding said drum and heating chambers and adapted to collect the gas or vapor developed from the loose material, and plungers radially reciprocating within said jacket in position for pressing loose material into the chambers for the loose material.

4. An apparatus for heating loose material, comprising a vertical rotary drum provided with annular heating chambers located one above the other and spaced from each other to provide chambers for the loose material, heating means for said heating chambers, a hopper means for supplying the loose material to the chambers provided between the heating chambers simultaneously, means to remove the loose material from said chambers simultaneously to the outlet, a stationary jacket surrounding said drum and heating chambers and adapted to collect the gas or vapor developed from the loose material, and plungers radially reciprocating within said jacket in position for pressing loose material into the chambers for the loose material, said plungers being displaced with relation to each other externally of the drum.

5. An apparatus for heating loose material comprising a vertical rotary drum provided with annular heating chambers located one above the other and spaced apart to provide intermediate chambers for said loose material, heating means for said heating chambers, said drum having vertical passages some of which are open at the bottom and in communication with said intermediate chambers, the remaining passages being in

communication with said intermediate chambers and being open at the top to deliver to the outlet of the drum, means for supplying the loose material to said intermediate chambers, means for removing the loose material from said intermediate chambers, and a

bers for collecting the vapors expelled from the loose material during heating.

In testimony whereof I hereunto affix my 10
signature.
